UNITED STATES PATENT OFFICE.

EDWARD KUPFERLE, OF ST. LOUIS, MISSOURI.

HOSE-NOZZLE.

1,076,128.

Specification of Letters Patent. Patented Oct. 21, 1913.

Application filed July 1, 1910. Serial No. 569,900

To all whom it may concern:

Be it known that I, EDWARD KUPFERLE, a citizen of the United States of America, residing in the city of St. Louis, in the State of Missouri, have invented certain new and useful Improvements in Hose-Nozzles, of which the following is a full, clear, and exact description, reference being had to the accompanying drawing, forming part of this 10 specification.

My invention relates to a hose nozzle provided with a strainer and an automatic cut off in proximity to the strainer adapted to control the flow of liquid therethrough, the 15 cut off being so mounted and governed as to provide for its preventing flow of liquid through the strainer when there is absence of pressure in the strainer housing and adapted to be opened by virtue of liquid under pressure introduced into the strainer housing and flowing therefrom through the strainer and past the cut-off.

The drawing is in part a longitudinal section and in part an elevation of my device. 25 In the drawing:—1 designates an elongated cylindrical strainer housing having a correspondingly shaped chamber 1^a and to one end of which a hose 3 is connected by a screw threaded end 3^a engaging the internally screw threaded neck of the strainer housing. The strainer housing is provided at its end opposite that to which the hose 3 is connected with an internally threaded head 2.

35 4 designates a valve housing provided with a screw threaded neck 5 fitted within the internally screw threaded head of the strainer housing 1. At the upper end of the neck 5 is an annular flange 6.

40 7 is an elongated strainer, preferably of frusto-conoidal shape occupying the housing chamber 1^a and the lower open end of which is fitted and attached to the flange 6 so that it is held centrally within the 45 strainer housing. At the bottom of the neck of the valve housing 4 is a valve seat 8.

9 is a cut-off valve arranged in the valve housing 4 and normally held against the valve seat 8 by an expansion spring 10. 50 The stem 9' of the cut-off valve is slidably mounted in an annulus 11^b in the spider 11^a of a valve supporting ring 11 in which the valve stem 9' is slidably fitted. The annulus 11^b has a reduced portion 11^c providing a seat 55 for the expansion spring 10. The valve supporting ring 11 is screw threaded at its

upper part so as to fit in the internally screw threaded lower part of the valve housing 4 and its lower part has a screw threaded neck.

12 is a discharge pipe attached to the screw threaded neck of the valve supporting ring and normally in communication therethrough with the interior of the valve housing 4.

In the practical use of my strainer and cut off, the cut off valve 9 is normally maintained in a closed position through the medium of the spring 10 so that the face of the valve rests against the valve seat 8 and prevents the flow of liquid that is not under pressure from the interior of the strainer housing to the valve housing, and therefrom to the discharge pipe. When, however, liquid is conducted under pressure through the hose 3 to the strainer housing, it is forced through the strainer 7 and pressure against the cut off valve 9 causes said valve to be unseated, with the result that the liquid, immediately after being strained, is permitted to flow to the discharge pipe and be delivered therefrom to the point at which delivery of the strained liquid is to be made. 75 It will be apparent that immediately upon the discontinuance of exertion of pressure upon the liquid in the strainer housing, the cut off valve is returned to its seat by virtue of the action thereagainst of the spring 10 discontinuing flow of the liquid from the strainer housing.

My strainer and housing is primarily intended for use in straining gasolene that is to be placed in the tanks of automobiles, and in such use of the device the hose 3 attached to a suitable type of pump used in connection with a gasolene reservoir, and the pressure for forcing the gasolene through the strainer and opening the cut off valve 9 is, therefore, obtained in the operation of said pump. It is obvious, however, that the strainer and cut off may be used for straining other liquids than gasolene and for use in other instances than that herein specifically mentioned.

I claim:—

A hose nozzle of the character described comprising an elongated strainer housing having a correspondingly shaped chamber, and formed with an internally screw threaded neck at one end and an internally screw threaded head at the other end, a valve housing having a screw threaded neck at one end fitting the internally screw threaded

head of the strainer housing, and provided with an annular flange and an internal screw thread at the other end, a strainer of frusto-conoidal shape fitted to the annular flange, 5 a valve supporting ring seating against the outer end of the valve housing having a screw threaded inner part fitting the internal screw thread of the valve housing and a

spider formed with an annulus, a spring cut-off valve having a stem slideable in the annulus and a spring seating around the annulus between the spider and the valve.

EDWARD KUPFERLE.
